UNITED STATES PATENT OFFICE.

WALTER G. WILLIAMS, OF ROXBURY, MASSACHUSETTS.

WOVEN PILE FABRIC.

1,201,071.

Specification of Letters Patent. Patented Oct. 10, 1916.

Application filed November 29, 1915. Serial No. 63,932.

To all whom it may concern:

Be it known that I, WALTER G. WILLIAMS, a citizen of the United States, residing at Roxbury, in the county of Suffolk and State 5 of Massachusetts, have invented a new and useful Woven Pile Fabric, of which the following is a specification.

This invention relates to a woven pile fabric of the type in which the pile loops or 10 tufts are formed from pile warp threads. It is immaterial in the consideration of my invention whether the loops are cut as in Wilton or velvet carpet or whether they remain uncut as in carpet of the Brussels type.

15 It is the object of my invention to improve the arrangement and disposition of the several component parts of the fabric to the end that the pile loops or tufts may be most securely bound to the stuffer warps which 20 give body to the fabric, and also that the loops or tufts may cover the fabric in a manner more effectually to conceal the coarse material forming the back or frame of the fabric.

25 With this object in view my invention relates to certain arrangements and combinations of the parts of the fabric which will be hereinafter described and more particularly pointed out in the appended claim.

30 The preferred form of my invention is shown in the drawings, in which—

Figure 1 is a longitudinal sectional elevation of a portion of the fabric embodying my invention, and Fig. 2 is a top plan view of the fabric.

Referring to the drawings the fabric comprises stuffer warps S, pile warps P, two sets of binder warps B and B', and upper and lower filling threads or wefts F and F'. 40 The stuffer warps S extend through the center of the fabric between the upper and lower wefts F and F', and the pile warps P are disposed in loops around the upper wefts F.

The binder warps B and B' are alternately disposed throughout the fabric, each binder warp B underlying a single weft F' and then passing over two adjacent upper wefts F. The warp is then brought down around the next alternate lower weft F'. The binder warps B' are similarly disposed, but underlie the intervening alternate lower wefts F', and furthermore the successive pairs of upper wefts engaged by the binder

warps B' are also grouped alternately with those engaged by the binder warps B. A 55 single binder warp B or B' is disposed between each two adjacent rows of pile loops as clearly shown in Fig. 2. Reference to this figure will show that adjacent binder warps B and B' engage the filling threads or wefts 60 F on each side of each pile loop P, and furthermore that they thus engage the weft F on opposite sides thereof, so that the upper wefts F are forced into the irregular or zigzag arrangement shown in Fig. 2. This 65 moving of the weft threads out of their normal straight-line position causes slight changes in the angular position of the pile loops P, as indicated in Fig. 2. With this arrangement of the component parts of the 70 fabric, the pile loops P are very securely bound upon the stuffer warps S and their slightly irregular arrangement enables them to more effectually conceal the structural lines of the backing or frame of the fabric. 75 The disposition of a single binding warp only between each two adjacent rows of pile loops is also of the utmost importance in securing a satisfactory covering of the fabric, as it reduces to a minimum the space intervening between adjacent rows of pile loops.

It is immaterial for the purposes of my invention whether the loops are left uncut as indicated at P in Fig. 1, or whether they 85 are separated as at P' to form pile tufts. It is furthermore immaterial whether the several elements of the fabric herein described are formed of single threads or of a plurality of threads associated together and co-acting 90 as a single element. Accordingly the words "warp" and "weft" as used in the claim are to be understood as covering either a warp or a weft composed of a single strand or composed of a plurality of strands acting 95 as a unit.

Having thus described my invention what I claim and desire to secure by Letters Patent is:—

A woven pile fabric comprising stuffer 100 warps, binder warps, pile warps, and upper and lower filling threads or wefts, said upper wefts overlying the stuffer warps and binding the pile loops thereon, said lower wefts directly underlying said stuffer warps, 105 and said binder warps being arranged in two

series and being positioned alternately between successive adjacent rows of pile loops, transversely adjacent binder warps underlying and engaging alternate single lower wefts and overlying and engaging all of the upper wefts in alternately grouped pairs, whereby each pile loop is disposed between

adjacent binder warps which engage the upper weft associated with said loop on each side of the pile loop and on opposite sides of said weft thread.

In testimony whereof I have hereunto set my hand.

WALTER G. WILLIAMS.
